MEASURING TAPE

Michel Quenot, Besancon (Doubs), France, assignor to
Etablissements Quenot & Cie, Besancon, France, a firm
of France

Filed June 23, 1964, Ser. No. 80,530

Claims priority, application France Feb. 6, 1964

Term of patent 14 years

(Cl. D52—1)

FIG. 1

FIG. 2

FIG. 3

FIG. 1 is a side view of a measuring tape showing my new design;

FIG. 2 is an end view thereof;

FIG. 3 is a side perspective view thereof.

The undisclosed side of the measuring tape is substantially the same in appearance as the side shown.

I claim:

The ornamental design for a measuring tape, as shown and described.
